STAGE BACKDROP

Albert Ganz, North Bergen, N. J.

Application March 12, 1952, Serial No. 276,137

1 Claim. (Cl. 272—11)

1

This invention relates to stage back drops or backgrounds such as are provided in conjunction with an act or performance on the stage of a theater, although the invention is also adapted to be provided in miniature as a toy or amusement device.

One object of the invention is the provision of such a background which, when viewed by an observer positioned in front thereof while a light such as, for example, a spotlight is projected thereon, particularly in an otherwise darkened interior, will give the appearance of a glowing rainbow and of birds flying in an arc just above the rainbow, the latter also being preferably glowing. The glowing effect of the rainbow and the birds is achieved by means of a coating of phosphorescent material or paint of suitably mixed colors to obtain the desired colors of the rainbow, or other desired combinations; in fact, the rainbow and the birds will actually glow and give off variegated colors in the dark without the spotlight but the effect is enhanced with the latter so that when the spotlight is projected upon only a small area as, for example, upon a star performer on the stage, the remainder of the phosphorescent background will glow. The effect is one of great beauty and appeal.

Another object of the invention is the provision of means for attaining the above results including means for activating figures representing birds to move as above-mentioned in simulation of birds in flight.

The above as well as additional and more specific objects will be clarified in the following description wherein characters of reference refer to like-numbered parts in the accompanying drawing. It is to be noted that the drawing is intended solely for the purpose of illustration and that it is therefore neither desired nor intended to limit the invention necessarily to any or all of the exact details of construction shown or described except insofar as they may be deemed essential to the invention.

Referring briefly to the drawing, Fig. 1 is a fragmentary front view of a theater stage having the backdrop of this invention mounted thereon.

Fig. 2 is a perspective view of the complete backdrop as a unit, in which form it may be provided on a theater stage or, in miniature, as a toy.

Fig. 3 is a fragmentary perspective view of the said backdrop unit, with parts broken away to expose other parts, and partly in section.

Fig. 4 is a sectional view taken on the line 4—4 of Fig. 2.

2

Fig. 5 is a sectional view taken on the line 5—5 of Fig. 3.

Fig. 6 is a sectional view taken on the line 6—6 of Fig. 5.

Referring in detail to the drawing, the numeral 10 represents a base on which the entire backdrop, which may be unitary with the base, is supported. A wall 11 extends from the forward edge of the base and the intermediate portion 12 is arcuately rounded at the top with only the end portions 13, which are adapted to be concealed behind the wings of the stage, in whole or part, of a relatively lower height than the arched portion. Painted on the front surface 15 of the wall 11 is a representation of a rainbow 14, the various arcuate stripes thereof being provided in the form of suitably colored phosphorescent paint.

Behind the wall 11 is a second and higher wall 15 having a continuous or endless slot 16 cut therethrough, consisting of a lower horizontal section 17 and an upper arcuate section 18. A third wall 19, rearward of the wall 15 and supported on one or more uprights 20, serves by means of a plurality of horizontal brackets 21, to hold the central portion 22 within the slot 16, upright within the plane of the wall 15. The wall 19 has, except for its thickness, the same conformation and dimensions as the cut-out portion 22 of the wall 15 and the lower horizontal edge 23 thereof lies in the same horizontal plane as the lower horizontal edge 24 of the portion 22.

The surrounding edge of the wall 19 serves as a continuous guide or race for a sprocket chain 25 of more or less standard construction. To facilitate movement of the chain around the smooth edge of the wall 19, the transverse pins which, of course, are standard parts of sprocket chains, are provided in the form of ball bearing rollers 26 as shown in Fig. 5. At one end of the wall 19 a cut-out 28 is provided therein, in which a sprocket wheel 27 is rotatably held on the end of a shaft 29. The wheel 27 is shown only for one end of this wall, in Fig. 3, as it should not be necessary to repeat the showing of such a wheel at the other end if such should be desired. However, the shaft 29 of the wheel 27 is elongated and extends rearward, and on its rear end is a pulley 30 connected by a belt 31 to the shaft of an electric motor 32. The motor thus serves to drive the chain 25 around the edge of the wall 19.

At spaced intervals along the chain 25, stems 33 are provided rigid with the chain and extending horizontally therefrom through the continuous slot 16. Figures representing birds in flight,

shown at 34, are rigid on the free ends of these stems and are, hence, positioned in front of the wall 15. The outer surfaces of these figures, which face forward of the stage, are also suitably coated with phosphorescent paint. It is to be noted that although the centers of curvature of the slot 16 and the arched portion 12 of the wall 11 are in alignment, the radius of curvature of the former is greater than that of the latter, so that the path of the moving bird figures 34 is spaced from the rainbow 14 and the birds are thus visible above the latter.

All of the bird figures are rigid on their stems 33 and the stems are rigid on the chain 25, and all the figures are positioned so as to be moved by the chain in a continuously forward direction. Thus, in the illustration, the birds 34 will move from right to left, Fig. 2, through the arc 18 of the slot 16, and they will move from left to right along the horizontal slot 17. However, since these figures are concealed from observers when they move in the slot 17, by the wall 11, the birds will appear to be in continuous arcuate flight along the slot 18, from right to left.

In practice, all surfaces of the walls 15 and 11 except for the rainbow 14, will be covered or coated with a light-absorbing black coating so that they will be invisible to the spectators, and with proper design and construction of the device the edges of the slot 16 will also be invisible. That side of the sprocket chain 25 which faces forward toward the wall 15 may also be coated with a black light-absorbing coating.

Thus a very effective backdrop has been provided, either for use on a theater stage or for use as part of a toy or amusement device. Obviously, modifications in form or structure may be made without departing from the spirit or scope of the invention.

I claim:

A backdrop comprising a base, a front wall extending upward from said base, the upper intermediate portion of said front wall being arcuate, a second wall positioned behind and parallel with

said front wall, said second wall extending upward from said base and having a continuous endless slot therethrough comprising an upper arcuate portion concentric with but of greater diameter than said arcuate upper portion of said front wall and a lower horizontal portion extending between the ends of said upper arcuate portion, support means positioning the inner portion of said second wall defined by said slot in the same plane as said second wall, a plurality of spaced stems extending rearward through said slot, figures such as, for example, those of birds in flight rigid on the forward ends of said stems, and means positioned rearward of said second wall for moving said stems continuously unidirectionally along said slot, said means comprising a sprocket chain having the rear ends of said stems rigid therewith, a third wall having the same conformation as said inner portion of said second wall positioned rearward of and parallel with said second wall and with the surrounding edge thereof in alignment with said slot, supports supporting said third wall above said base, said sprocket chain being trained about said surrounding edge of said third wall, said third wall having a cut-out at one end thereof at the intersection of said horizontal slot portion with said arcuate slot portion, a sprocket wheel rotatably mounted in said cut-out in the plane of said third wall, said chain being trained about said sprocket wheel, a shaft extending from said sprocket wheel, and means for rotating said shaft.

ALBERT GANZ.
